US00D586374S

(12) **United States Design Patent**
Kim

(10) **Patent No.:** US D586,374 S
(45) **Date of Patent:** ** Feb. 10, 2009

(54) **DIGITAL CAMERA**

(75) Inventor: **Tae Ho Kim**, Gyeonggi-do (KR)

(73) Assignee: **Samsung Electronics Co, Ltd. (KR)**

(**) Term: **14 Years**

(21) Appl. No.: **29/244,545**

(22) Filed: **Dec. 9, 2005**

(30) **Foreign Application Priority Data**

Sep. 6, 2005 (KR) 30-2005-0030184

(51) **LOC (9) Cl.** **16-01**

(52) **U.S. Cl.** **D16/202; D16/218**

(58) **Field of Classification Search** D16/200-206,
